Primary Examiner — Raphael Barkai*Assistant Examiner* — Randall Gholson(74) *Attorney, Agent, or Firm* — Jason R. Sytsma; Shuttleworth & Ingersoll, PLC(57) **CLAIM**

The ornamental design for a rotary ratchet wrench, as shown.

DESCRIPTION

FIG. 1 is a perspective view of a wrench;

FIG. 2 is a top view thereof;

FIG. 3 is a side view thereof; and,

FIG. 4 is a front view thereof.

Petitioner disclaims the shape and configuration of the features of those portions shown in broken lines.
